Primary Examiner — Sandra S Snapp*Assistant Examiner* — Mehri F Bajoul(74) Attorney, Agent, or Firm — Global IP Counselors, LLP(57) CLAIM

The ornamental design for a pet toy, as shown and described.

DESCRIPTION

FIG. 1 is a top perspective view of a pet toy in accordance with our new design;

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a side view thereof; and,

FIG. 8 is a side view thereof.

The broken lines shown in the drawings depict portions of the pet toy that form no part of the claimed design.

The words “Chuckit!” and “ULTRA” depicted in broken lines also form no part of the claimed design. “Chuckit” is a word mark owned by DOSKOCIL MANUFACTURING COMPANY, INC. CORPORATION.

1 Claim, 5 Drawing Sheets(56)
